UNITED STATES PATENT OFFICE.

HENRY G. HILLMAN, OF NEW YORK, N. Y., ASSIGNOR TO JOHN TEFFT CLARKE, OF NEW YORK, N. Y.

SAFETY DEVICE.

1,171,338.

Specification of Letters Patent.

Patented Feb. 8, 1916.

Application filed April 22, 1911. Serial No. 622,709.

To all whom it may concern:

Be it known that I, HENRY G. HILLMAN, a citizen of the United States, residing at New York, in the county of New York 5 and State of New York, have invented certain new and useful Improvements in Safety Devices, of which the following is a full, clear, and exact description, such as will enable others skilled in the art to which it 10 appertains to make and use the same.

This invention relates to safety devices, and with regard to the more specific features thereof, a device or apparatus adapted to be applied to vehicles.

15 One of the objects of the present invention is to provide a simple and practical device whereby a movement of the vehicle is impossible when the entrances thereto are unprotected against the entrance or exit of 20 passengers.

Another object is to provide a safety device that will be cheap to construct and inexpensive to install.

A further object is to provide a device 25 of the above character particularly applicable to electrically operated elevators.

Another object is to provide an improved and practical arrangement of electric circuits in safety devices for electric elevators.

30 Other objects will be in part obvious and in part hereinafter pointed out.

The invention accordingly consists in the features of construction, combinations of elements and arrangement of parts which 35 will be exemplified in the construction hereinafter set forth, and the scope of the application of which will be indicated in the following claims.

In the accompanying drawing, wherein is 40 shown one of various possible embodiments of this invention, Figure 1 is a diagrammatic view showing an electric elevator system with such parts of the present invention applied thereto as are necessary 45 to understand its operation; Figs. 2 and 3 are views, partly in section, at right angles to each other, of a preferred form of door contact.

Similar reference characters refer to similar parts throughout the different views of the drawings.

While the present invention is herein illustrated and described with reference to a safety device particularly applicable to electric elevators, it is, of course, to be under-

stood that the device may be applied to other forms of vehicles, as subway trains, with but slight changes in the arrangement of parts. It is likewise to be understood that where the term "elevator-car" or "car" is used in 60 the claims, it is not to be limited to the form of vehicle herein shown.

Referring to the drawings in detail, and particularly to Fig. 1, 1 represents a generator or other source of electrical power, connected by suitable wiring with the building or place of installation of the elevator.

A master switch 2 is provided in this circuit for completely shutting off the current supply from both the safety circuit and 70 hoisting means when the elevator is to be stopped for the night, for example. Adjacent the master switch 2 is another circuit forming the door circuit, one part 3 of which passes to a point in the elevator shaft sub-

stantially half the height of the building, where it is connected by a flexible cable with an elevator car 4. Within the car is a normally closed push button switch 5, from 75 which leads a second wire back through the flexible cable to each of a plurality of gate contacts 6, one located at each floor. These

gate contacts are normally open, as shown, for example, on the first and third floors of the diagram, but are so constructed, as will 80 be hereinafter explained more in detail as to 85

close the circuit the moment any door 7 is 90 opened, as shown on the second floor of the diagram. It is thus seen that when the circuit is closed by any one of the gate contacts, the second terminal of which is connected 95 with a wire 8 running to a solenoid 14, the solenoid will be energized, thereby

raising the core to break the circuit at switch 10. One of the terminals of the switch 10 100 leads directly to the elevator control circuit 11, in which is located the controller of the car. The other terminal is connected by wire 12 with the elevator control magnets.

These features are shown in a diagrammatic conventional way in Fig. 1, where 25 indicates the controller on the car, 26 the car motor, and 27 the control device which includes control magnets 28, 29, 30 and 31. As here 105 shown, there are four of these control magnets, two of them, as 28 and 29, being known as "up" magnets, and two of them, as 30 and 31, being known as "down" magnets.

One arrangement of accelerating devices is shown at 32, the function of which is to start 110

the elevator motor gradually in the desired direction.

Referring to the solenoid more in detail, a coil 14 is provided within the casing 9 surrounding a movable core 15 normally held in lowered position by the action of a spring 16 forcing the same downwardly. At the upper part of the solenoid is a small stationary part 17 of the core adapted to 10 act as a buffer when the core 15 is suddenly raised, by the energizing of the solenoid. A small disk 18 of a diameter less than that of the core is preferably interposed between the parts 15 and 17 to prevent a flattening 15 and spreading of the ends of the contacting metals.

Each door contact, Fig. 1, comprises a base 19 of insulating material, at one end of which is a terminal clip 20 connected with 20 the wire from the flexible cable, adapted to receive the end of a pivoted knife switch 21 secured to a second terminal 22 connected to the wire 8. A spring 23 connected with the switch blade 21 and the base 19 tends to 25 keep the switch in closed position. A block of insulating material 24 is normally engaged by the door 7 when closed, to hold the switch in open position against the tension of the spring. As soon, however, as the 30 door is opened an inch or more, the switch will immediately close the circuit under the action of the spring 23.

The push button 5 within the car is for the purpose of breaking the door circuit to 35 deenergize the solenoid 9 should the operator of the car at any time desire to move the elevator, and at the same time permit the door to remain open, as, for example, when a door accidentally becomes open a car 40 would otherwise be suspended between floors, or when it is desired to have a workman get on top of the car for the purpose of making repairs. The carbon contacts at the switch 10 complete the circuit through the 45 elevator control circuit, whereby the car may be moved up and down at will by the motor connected in the motor circuit 13.

In Figs. 2 and 3 is shown a modified form of door contact. In this modification a lug 50 36 is pivotally mounted at 37 in one corner of rectangular metallic box 38. This lug 36 carries a knife switch 39 adapted to coat with two terminal clips 40 and 41 to complete a circuit from one to the other in the 55 manner above described in connection with the modification shown in Fig. 1. A spring 42 normally holds the switch in closed position and is adapted to be compressed when the circuit is broken as the door is opened.

60 If at any time it is desired to disconnect the safety door circuit and operate the car in the usual manner without the safety device, the lug 36 of this form of door contact may be raised until a hole 43 therein registers with a hole 44 in the cover of the casing

38. A pin or nail is inserted through these registering holes which holds the knife switch 39 out of contact with the terminals 40 and 41, thus maintaining a broken circuit at all times.

As herein shown the safety door circuit may be a branch or shunt circuit from the main power circuit, it being assumed that in the modification shown the voltage of the power circuit is insufficiently high to cause 70 an appreciable arc, as the contacts are broken at any of the various places in the circuit. If, however, the system should be applied to a tall building in which the voltage for driving the motor for hoisting the 80 elevator-car was much higher than in the usual lighting circuit it would then be desirable to take the current supply from an independent lighting circuit as shown in Fig. 1 instead of directly from the generator 1. 85

The operation of this device is substantially as follows: The elevator car is moved up and down by the action of any electrical source of power, as a motor, in the circuit 13 which is directly under the control of a 90 second circuit 11 and 12, familiarly known as the controlling circuit. If a car is stationary at one of the floors and the door 7 opened, the gate contact 6 will complete the circuit to energize the solenoid 9, thus breaking the contact at the switch 10. This contact being broken, of course, prevents the operation of the controlling circuit, so that it is impossible to start the car by movement of the controller. As soon, however, as the 100 door is closed, the door contact 6 will move to the position shown on either the first or third floor, Fig. 1, thus breaking the door circuit and deenergizing the solenoid, whereby the switch 10 closes the motor-controlling circuit, thus permitting the car to be started at will. As already explained, if it should be desired to start the car while the door is open, the push-button 5 may be depressed, thus keeping the circuit broken 110 as long as it is desired to move the car.

The invention herein shown employs a normally open circuit, yet it is to be understood that by reversing certain parts a normally closed circuit will act in a similar 115 manner although with greater expense.

It is thus seen that this invention accomplishes among others, all the objects and advantages set forth in a practical and simple manner.

As many changes could be made in the above construction and many apparently widely different embodiments of this invention could be made without departing from the scope thereof, it is intended that all 125 matter contained in the above description or shown in the accompanying drawings shall be interpreted as illustrative and not in a limiting sense.

It is also to be understood that the lan- 130

guage used in the following claims is intended to cover all of the generic and specific features of the invention herein described, and all statements of the scope of the invention which, as a matter of language, might be said to fall therebetween.

Having described my invention, what I claim as new and desire to secure by Letters Patent is:

- 10 1. A safety system for vehicles comprising, in combination with a vehicle, an electric motor for said vehicle, a power circuit for said motor, a door controlling entrance to and egress from said vehicle, a door circuit operated by said door, a controlling device for controlling the direction and application of power through said power circuit to said motor, a control circuit for said controlling device which includes a hand controller on the vehicle, and an electro-magnetic switch for operating said control circuit and having its coils energized from said door circuit.
- 15 2. A safety system for vehicles comprising, in combination with a vehicle, an electric motor for said vehicle, a power circuit for said motor, a door controlling entrance to and egress from said vehicle, a door circuit operated by said door, a controlling device for controlling the direction and application of power through said power circuit to said motor, a control circuit for said controlling device to automatically start the motor gradually and to stop said motor, said control circuit including a hand controller on the vehicle, and an electro-magnetic switch for operating said control circuit and having its coils energized from said door circuit.
- 20 3. A safety system for vehicles comprising, in combination with a vehicle adapted to move from one station to another, an electric motor for said vehicle, a power circuit for said motor, a door at each station controlling entrance to and egress from the vehicle, a door circuit operated by a door, an electro-magnetic controlling device for automatically starting the motor gradually and stopping said motor, said control circuit including a hand controller on the vehicle, and an electro-magnetic switch for operating said control circuit and having its coils energized from said door circuit.
- 25 4. A safety system for elevators comprising, in combination with an elevator car, an electric motor for said car, a power circuit for said motor, a plurality of floor doors, a

door circuit operated by said doors, a controlling device for controlling the application of power through said power circuit to said motor, a control circuit for said controlling device extending from the car to said device, a hand controller located on said car in said control circuit, and an electro-magnetic switch for operating said control circuit and having its coils energized from said door circuit.

5. In a safety device of the character described, in combination, an elevator car, a plurality of floor doors, a door circuit, a switch at each door in said circuit actuated by the opening and closing of the door, means for moving the elevator car, an operating circuit therefor, a controlling device for said operating circuit, a controlling circuit for said operating device, a manual controller located in the car and included in said controlling circuit, and means independent of said manual controller to open said controlling circuit when the door is opened.

6. In a device of the character described, in combination, an elevator car, a door at each floor, motive controlling means, a control circuit, a door circuit, a contact at each floor adapted to be operated by the opening of the door to operate the door circuit, and means comprising a switch device actuated through the door circuit to open said control circuit whereby a movement of the car is prevented when the door is open.

7. In a safety device of the character described, in combination, an elevator car, a plurality of floor doors, a door circuit, a switch at each door in said circuit actuated by the opening and closing of the door, means for moving the elevator car, an operating circuit therefor, an electro-magnetic controlling device for automatically admitting current in said operating circuit gradually and cutting off said current, a controlling circuit for said operating device, a manual controller located in the car and included in said controlling circuit, and an electro-magnetic switch in said controlling circuit having its winding in said door circuit.

In testimony whereof I affix my signature, in the presence of two witnesses.

HENRY G. HILLMAN.
